LAUNDRY IRONER RACK

Ralph J. Herrcke, Los Angeles, Calif.

Application July 3, 1948, Serial No. 36,879

3 Claims. (Cl. 214—1)

1

This invention relates to laundry apparatus, and particularly to a so-called "shake-out" rack for supporting shake-out poles upon which flat-work laundry is draped, and for guiding the loaded poles to a flat-work ironing machine.

It is the common procedure in ironing relatively large flat-work, such as bed sheets, bed spreads, etc., to shake out the damp flat-work upon a table and thereafter drape the pieces over shake-out poles which are supported upon a shake-out rack, the rack having inclined guides for supporting the ends of the poles and along which the loaded poles can be slid toward the ironing machine. Upon reaching a point on the guides adjacent the ironing machine, the ends of each pole are lifted from the guides and the pole transferred bodily from the rack to the ironing machine where its ends are placed in brackets on the machine, the damp flat-work being then shaken out and its edges inserted in the machine to be automatically ironed. It will be apparent that poles, over which a number of damp bed sheets are draped, are extremely heavy and for this reason the task of transferring the loaded poles from the rack to the machine is a laborious one and often results in serious injury to the workers. Moreover, due to the unwieldiness of the pole and its load of flat-work, the workers find it extremely difficult to guide the ends of the pole into the brackets or holders on the ironing machine and it is not uncommon to drop one or both ends of the pole, thus allowing the work to strike the floor and become soiled. It would therefore seem that the solution to this problem is to position the shake-out rack so that the delivery end of its guides is disposed in proximity to the holders on the ironing machine so as to avoid the necessity of manually lifting the poles and transferring them to the holders. However, such an arrangement has heretofore been deemed impractical for the reason that the workers must assume a position directly in front of the ironing machine in order to allow them to simultaneously shake out and lead the flat-work onto the feeding apron of the machine and, if the delivery end of the rack is thus disposed, such position of the workers is impossible. In addition, the amount of flat-work fed by the workers has been limited by the ability of the workers to lift the poles and the work supported thereby.

It is an important object of this invention to provide a shake-out rack, for use with an ironing machine, which will eliminate all the faults of previously used racks as discussed above.

Another object is to provide a shake-out rack

2

which is adapted to be disposed adjacent to but spaced at a suitable distance from the work-receiving end of a flat-work ironing machine, the space between the rack and the machine being normally closed by gates which, when in extended position, form continuations of the guide means of the rack. By this means, the loaded poles can be slid throughout the entire distance from the shake-out table to the ironing machine so that lifting of the loaded poles is unnecessary and physical exertion on the part of the workers is practically eliminated and the amount of work supported by each pole can be greatly increased. Moreover, since the loaded poles are fully supported during their transfer to the ironing machine, dropping of the poles and the flat-work held thereby onto the floor is wholly avoided. A related object is to provide, in a shake-out rack, gate means which can be readily pivoted to retracted or inoperative position away from the ironing machine so as to open the space between the rack and the machine, thus enabling the workers to walk into the space or pasageway and assume a position directly in front of the ironer, at which station they can further shake out the flat-work and place it on the feed apron of the machine. Following the transfer of the flat-work from the pole located on the ironing machine, the workers take up positions at the sides of the machine, at which time the empty pole is lifted from the machine and returned to the shake-out rack and placed on an auxiliary guide which directs successive poles to an end of the rack to be again loaded, the auxiliary guide being of novel construction, and this is another object of the invention.

A further object of the invention is to provide a shake-out rack in which the guide means for guiding the loaded and empty shake-out poles are inclined to facilitate movement thereof, and in which stop means are provided for preventing displacement of the poles from the guide means. Another object in this connection is to provide gate means having stop shoulders thereon, and means for raising the gates to a slight degree during their pivotal movement to retracted position so as to dispose the shoulders above the path of sliding movement of the loaded poles along the guide means of the rack toward the ironing machine. By this means, the loaded poles are thus retained on the rack and prevented from sliding therefrom when the gates are opened. A further object in this connection is to provide inter-engaging cam means on the

rack and gates for elevating the gates so that the gates are automatically and positively raised by the simple act of swinging them to open position.

A still further object of the invention is to provide a shake-out rack which comprises a pair of independent frame members, each having a base for supporting it on the floor and each provided with a gate pivoted at one end thereof. By this construction, the frame members, which are comparatively light in weight, can be easily slid along the floor to an operative position adjacent the ironing machine or moved away from the machine and transferred to another machine when such a procedure is necessary. The rack is thus rendered more portable and, as a result, less physical effort is required to set up the rack in various locations. Moreover, the individual frame members can be spaced apart at any desired distances so that shake-out poles of different lengths can be supported therebetween.

Further objects of the invention will be apparent from the following detailed description and from the drawings, which are intended for the purpose of illustration, and in which:

Fig. 1 is a perspective view of my improved shake-out rack, showing it employed for feeding shake-out poles to a flat-work ironing machine;

Fig. 2 is a perspective view of the delivery end of one of the frame members, showing the gate in extended or operative position;

Fig. 3 is a view similar to Fig. 2 illustrating the gate in retracted or inoperative position;

Fig. 4 is an enlarged fragmentary view of the pivot means for the gate and also the cam means for raising the gate;

Fig. 5 is an enlarged cross-sectional view, taken on line 5—5 of Fig. 4; and

Fig. 6 is an end elevation of the lower portion of an alternative form of frame member for the rack, showing means for adjusting the height of the rack.

Referring to the drawings in detail, my improved shake-out rack 10 is herein shown as used in connection with a flat-work ironing machine 11, although the rack may be employed with other types of laundry and textile apparatus. The ironer 11 illustrated herein is of the conventional type having side frames 12, each provided with a bracket 13 having a slot 14 therein adapted to receive the ends 15 of shake-out poles 16 so as to support the latter, this structure being common to ironers now in use. The shake-out poles 16 are adapted to support bed-sheets, spreads and other flat textile articles 20 which are to be ironed, the damp flat-work pieces on the pole disposed in the slots 14 being shaken out by workers who stand in front of the machine. The ends of the pieces 20 are subsequently placed on a traveling feed apron 17 which then feeds the pieces through the machine to be ironed.

As is common practice in laundries, the shake-out rack is disposed in front of the flat-work ironer and is adapted to support a series of the loaded shake-out poles and to guide the same toward the ironer. At its side remote from the ironer, the shake-out rack has a rest or support upon which empty poles are held during the draping of the damp flat-work thereover, the flat-work being transferred from a shake-out table 21 disposed adjacent the support or loading side of the rack.

The improved shake-out rack 10 comprises a pair of unconnected frame members 24 and 25, each of which has a forward stanchion 26, a rearward stanchion 27 and a pair of horizontal con-

necting bars 28 and 29. The stanchions 26 and 27 are supported by transverse feet or bases 30 which rest upon the floor or other support and which may be readily slid therealong. Connected between the upper ends of the stanchions 26 and 27 of each frame member 24 and 25 is a third bar 32 which slopes downwardly from the rearward side to the front side of the frame member. The frame members 24 and 25 may be made from any suitable structural elements, such as angle-iron sections, but I prefer to fabricate them from tubular stock so as to avoid sharp corners, the tubes being welded or otherwise secured together in the assembled relationship shown in the drawings. The upper inclined bars 32 of the frame members 24 and 25 together provide an inclined primary guide upon which the ends 15 of loaded shake-out poles 16 are adapted to rest and along which the poles are capable of being slid toward the ironing machine 11 in the manner to be explained more fully hereinafter. The rearward ends of the guide bars 32 constitute supports 33 upon which the ends 15 of empty shake-out poles 16 rest during the draping of the flat-work 20 thereover. To prevent these poles from sliding off from the rearward side of the rack, I prefer to attach stop plates 34 to the stanchions 27, the upper ends of the plates projecting above the guide bars 32 for this purpose.

Substantially U-shaped brackets 36 are secured to the cross bar 28 of each frame member 24 and 25 and project laterally outward, then upward and terminate in inwardly directed portions 35 to which auxiliary longitudinal guide bars 37 are welded or otherwise secured. The guide bars 37 are disposed above the guide bars 32 and each has a forward horizontal portion 38 and a rearward inclined portion 39 which slopes downwardly toward the support 33. At the intersection between the horizontal and inclined portions 38 and 39, each auxiliary guide bar 37 has a raised lug 40 which serves as a stop for resisting unwarranted rearward sliding movement of the shake-out poles 16 from the horizontal portions 38 onto the inclined portions 39. Caps 41 applied to the forward ends of the horizontal portions 38 also act as stops for preventing forward sliding movement of the empty shake-out poles 16 from the rack.

Attached to the stanchion 26 of each frame member 24 and 25 is a vertical tube 45 in which is held a pivot stud 46, the stud projecting above the upper end of the tube (Fig. 4). The upper end of the tube 45 is provided with a notch 47, one side of which is inclined to provide a cam edge 48.

Pivotedly mounted on the pivot studs 46 of the frame members 24 and 25 are gates 50 and 51. Each gate 50 and 51 is made from tubular stock and is of substantially triangular shape. Each gate has a vertical leg 52, the lower end of which is rotatable on the pivot stud 46, a strap 53 secured to the stanchion 26 and surrounding the leg 52 adjacent its upper end providing additional support for the gate to adapt it for pivotal movement in a horizontal plane. Each triangular gate 50 and 51 has a second leg 54 which projects laterally and downwardly from the upper end of the leg 52 to provide an inclined secondary guide 65 along which the loaded poles 16 can be slid. A bar 55 extending between the legs 52 and 54 serves as a brace for the gate structure. The lower end of the vertical leg 52 is provided with a cam lug 56 adapted to be disposed in the notch 47 of the tube 45.

To apply the shake-out rack 10 to use in connection with the flat-work ironing machine 11, the individual frame members 24 and 25 are slid along the floor to a position in front of the machine and their gates 50 and 51 opened to extended position as shown in Figs. 1 and 2. By sliding the frame members forwardly and laterally, the outer ends of the guide bars 54 can be brought into register with the slots 14 of the ironer frame, that is, these ends can be so arranged relative to the slots that the ends 15 of a shake-out pole slid along and over the ends of the bars 54 will drop into the slots to be supported by the brackets 13.

After the frame members 24 and 25 have been thus adjusted with respect to the ironer and spaced apart from each other a distance which will permit the ends of the shake-out poles to rest upon the guide bars 32, 37 and 54, a series of the shake-out poles 16 are applied to the rack by merely placing them upon the auxiliary guide 20 37. The rack is then ready for operation.

During operation of the ironing machine 11, workers stand alongside the table 21 and as damp flatwork laundry is delivered to the table the workers shake out the pieces and drape them over a shake-out pole 16 which has been transferred from the upper guide 37 onto the supports 33 of the main guide bars 32. After this pole has been thus loaded, it is slid forwardly along the guide bar 32 and another pole is transferred from the guide bars 37 onto the supports 33 to be similarly loaded with flat-work pieces. As each loaded pole is slid forwardly along the guide bar and reaches the forward side of the frame members 24 and 25, workers stationed adjacent the ends of the rack exert force against the projecting ends 15 of the pole 16, thus causing the pole to slide down the inclined guide bars 54 of the gates 50 and 51, as indicated by broken lines in Fig. 2. Eventually, the 40 loaded pole 16 rides off the end of the guide bars 54 and its ends 15 drop into the slots 14 to mount the pole on the ironing machine. Thereafter, the workers push the guide bars 54 to swing the gates 50 and 51 inwardly to the retracted or inoperative position shown in Fig. 3 so as to effect an unobstructed passageway between the ironer and the rack. The workers are thus able to enter the space thus formed between the ironer and rack and to assume positions in front of the loaded 50 pole, whereafter the workers additionally shake out the flat-work and lead its edges onto the traveling apron 17 which then feeds the work through the ironer.

After the work has been transferred from the shake-out pole 16 onto the ironing machine 11, the workers exit from the passageway and swing the gates to the extended position shown in Fig. 1, thus closing the passageway and restoring the gates to first position. The workers then grasp the ends of the empty pole and lift the latter and deposit it on the forward end of the upper guide bar 37 to adapt the pole to be later slid rearwardly to loading position.

It will be observed by reference to Fig. 2 that when the gates 50 and 51 are in the extended or operative position, the rearward ends of their inclined guide bars 54 are disposed in alignment with the main guide bars 32 so that the bars 54 provide continuations of but are inclined at a somewhat steeper angle than the bars 32, this arrangement permitting free sliding movement of the loaded poles 16 to the ironing machine. However, as the gates 50 and 51 are pivoted to the retracted position shown in Fig. 3, their cam 70 75

lugs 56 ride out of the notches 47 along the cam faces 48 and come to rest upon the upper edge of the tubes 45. It is thus seen that during pivotal movement of the gates 50 and 51 to retracted position, they are automatically elevated, the effect of this action being to raise the rearward end of the guide bars 54 slightly above the main guide bars 32 to thus serve as stops or barriers against which the loaded poles 16 on the guide bar 32 must engage if they are inadvertently slid forwardly. By this provision, displacement of the loaded poles from the rack to cause possible injury to the workers located between the rack and the ironer is avoided.

The operation as explained above may be continued as long as there remains a supply of flat-work to be ironed, workers loading the work on the poles at the rearward or loading side of the rack 10 and pushing the loaded poles forwardly, and workers at the forward end of the rack then successively sliding these poles along the gates 50 and 51 and into the recesses 14, opening the gates, transferring the work from the pole to the ironer, closing the gates, and thereafter transferring the stripped pole from the machine to the guide bar 37. It is thus seen that the entire shaking out and feeding operation is systematically and expeditiously carried out. Moreover, since the loaded poles are fully supported during their entire travel from the loading position onto the ironing machine, it is unnecessary to lift the poles manually and thus the operation is accomplished without appreciable physical effort on the part of the workers and fatigue is thus reduced to a minimum.

Conventional shake-out racks commonly employed in laundry establishments have been impractical for the reason that the load of flat-work carried by each shake-out pole has been necessarily limited to the weight which could be safely lifted by two women workers. By the use of the present shake-out rack, the capacity of the work fed to the ironer is limited only by the ability of the shake-out poles to support the weight of the work. In other words, since the poles are no longer lifted by the operators but merely slid along the rack, the amount of damp work carried by each pole and fed by the women workers is increased to a great extent. For example, it has been determined that by use of the present improved rack, 75 damp bed-sheets, each weighing approximately 2½ pounds, can be safely supported by a 2 inch by 3 inch shake-out pole and readily slid along the guide bars to the ironing machine. It is thus seen that flat-work having a total of approximately 188 pounds can be conveniently and safely handled during each feeding operation and the productive capacity of the ironer is greatly increased. Since the loaded poles are fully supported at all times, possibility of the poles dropping onto the floor to soil the work carried thereby is avoided. The successful function of the rack is attributed to the provision of the gates 50 and 51 which, while serving primarily to support and guide the loaded poles onto the ironer, can be opened to provide a clear space between the rack and ironer to permit the workers to take up positions directly in front of the machine.

Referring now to Fig. 6, it is within the concept of my invention to provide means for adjusting the height of the shake-out rack so as to further facilitate movement of the shake-out poles along the guide bars and in accordance with the height of the ironing machine and the length of the

flat-work to be handled. In this modified construction, the feet or bases 60, which correspond to the similar elements 30 described before, carry vertical gusset plates 61 which, in turn, support a pair of bolts 62. The stanchions 63, which correspond to the stanchions 26, are provided with a series of apertures 64 through which the bolts 62 can be inserted to connect the stanchions to the bases. By this means the height of the shake-out rack can be readily varied in accordance with the requirements.

While I have herein shown and described the shake-out rack as embodied in a preferred form of construction, by way of example, it will be apparent that various modifications might be made therein which would fall within the scope of the invention. Consequently, I do not wish to be limited in this respect, but desire to be afforded the full scope of the appended claims.

I claim as my invention:

1. A shake-out rack adapted to support laundry shake-out poles and guide the same to a laundry machine, comprising: a frame adapted to be disposed adjacent the machine, said frame having a pair of laterally spaced, inclined, primary guide means upon which the ends of shake-out poles are adapted to rest and along which they can slide in a direction toward the machine; a pair of laterally spaced, vertical, pivot means carried by said frame at its side adjacent the machine; and substantially triangular gate means each having a vertical tubular leg pivoted on one of said pivot means, each of said gate means having a second leg providing a secondary, inclined guide means which provides, when each gate means is pivoted to an extended po-

sition, a continuation of said primary guide means along which the poles can be slid to the machine, said secondary guide means being of greater slope than said primary guide means, said gate means being adapted, when pivoted to retracted position against said frame, to effect an unobstructed passageway between the machine and said frame through which attendants of the machine can walk, each of said gate means having a stop shoulder adjacent the intersection of its legs, and including elevating means for raising said gate means during the pivotal movement of the latter to retracted position so as to dispose said stop shoulder in the plane of the shake-out poles disposed on said primary guide means and thus prevent sliding displacement of said poles from said primary guide means.

2. A rack as defined in claim 1 in which said elevating means comprises interengaging cam means on said pivot means and said gate means.

3. A rack as defined in claim 2 in which said interengaging cam means includes a cam lug on said vertical leg engageable with an annular cam edge on said pivot means.

25
